UNITED STATES PATENT OFFICE.

HARRY BURRIS, OF NEWCASTLE, INDIANA.

DESIGN FOR A BURIAL-CASKET.

45,551.

Specification for Design.

Patented Apr. 7, 1914.

Application filed February 6, 1914. Serial No. 817,073. Term of patent 7 years.

To all whom it may concern:

Be it known that I, HARRY BURRIS, a citizen of the United States, residing at Newcastle, in the county of Henry and State of Indiana, have invented a new, original, and ornamental Design for Burial-Caskets, of which the following is a specification, reference being had to the accompanying drawing, forming a part thereof.

The figure is a plan view of a burial casket, showing my new design.

I claim:

The ornamental design for a burial casket, as shown.

HARRY BURRIS.

Witnesses:

J. W. BLANSETT,
MINNIE BOYD.
